US0D1033365S

(12) **United States Design Patent** (10) Patent No.: **US D1,033,365 S**
(45) Date of Patent: ** Jul. 2, 2024

(54) **SPLITTER**

(71) Applicant: **PPC BROADBAND, INC.**, East Syracuse, NY (US)

(72) Inventors: **Jordan Caviness**, Liverpool, NY (US); **Steve Stankovski**, Clay, NY (US); **Paul Bailey**, Camillus, NY (US); **David Barany**, Syracuse, NY (US)

(73) Assignee: **PPC BROADBAND, INC.**, East Syracuse, NY (US)

(**) Term: **15 Years**

(21) Appl. No.: **29/821,546**

(22) Filed: **Dec. 30, 2021**

(51) LOC (14) Cl. **13-03**

(52) U.S. Cl.

USPC **D13/151**

(57) **CLAIM**

The ornamental design for a splitter, as shown and described.

DESCRIPTION

FIG. 1 is a front, top, left-side perspective view of a splitter; FIG. 2 is a rear, top, right-side perspective view thereof; FIG. 3 is a front elevational view thereof; FIG. 4 is a rear elevational view thereof; FIG. 5 is a right-side elevational view thereof; FIG. 6 is a left-side elevational view thereof; FIG. 7 is a top plan view thereof; and, FIG. 8 is a bottom plan view thereof. The dash-dash broken lines in the drawings illustrate portions of the splitter that form no part of the claimed design. The dot-dash broken lines illustrate the bounds of the claim and form no part of the claimed design.

1 Claim, 8 Drawing Sheets
